UNITED STATES PATENT OFFICE.

NORMAN OSCAR FLEMING, OF MANSFIELD, OHIO.

AUTOMATIC WATER-GAGE.

No. 821,709.

Specification of Letters Patent.

Patented May 29, 1906.

Application filed March 23, 1905. Serial No. 251,617.

To all whom it may concern:

Be it known that I, NORMAN OSCAR FLEMING, a citizen of the United States, residing at Mansfield, in the county of Richland and State of Ohio, have invented a new and useful Automatic Water-Gage, of which the following is a specification.

My invention relates to water-gages for steam-boilers, and has for its object to provide a gage that will automatically cut off the flow of steam and water if the glass tube is broken by any means.

A further object of my invention is to provide a water-gage so constructed that the flow of steam and water can be regulated, allowing the glass to heat gradually to the temperature of the boiler, so that all danger of the glass being broken by the rush of water and steam into a glass, as now is the case when a new one is inserted.

With these objects in view my invention relates to certain new improvements and construction of parts hereinafter described, and pointed out in the claims.

Referring to the drawings, A indicates the glass tube, B the upper casing, and C the lower casing, in which the glass tube is secured by the water-tight stuffing-boxes b and c, the casings being connected together by a guard-rod C', which protects the glass tube

A, each of the casings being provided with a screw-threaded plug D, connected to the boiler, and forms a passage E, which allows steam and water to enter through the passage F to the chamber G, which is provided with a screw-threaded offset G', on which is screwed a cap H, having the screw-threaded extension H', carrying the cut-off-valve stem I, the head I', which is seated when closed in

the valve-seat J', formed in the partition J' between the chamber G and the passage J, leading into the glass tube. On the extension H' of the cap H is screwed a hand-wheel K, provided with an outwardly-extending casing K', the end of which is provided with a set-screw K'', which engages the end of the valve-stem I. The stem I extends through the cap H and the plug H'', which is screwed into the recess H', compressing the packing

H'', and is surrounded by a coil-spring H'', which prevents the valve from closing accidentally when the boiler is cold or out of commission. The stem I is also provided with an enlargement I'', which always rests in the recess H'', forming a steam-tight joint.

The passage E and the passage J of the cas-

ing B are connected together by an auxiliary passage L, which is provided with a valve-seat I', in which is a needle-valve L'', the valve working in the extension E' of the passage E and is of the ordinary construction. By connecting the passages by the auxiliary passage controlled by a valve I provide means for allowing steam to enter the glass gradually, so that all danger of the glass tube being broken by the sudden rush of steam and water is prevented. At the end of the passage E, I provide a valve-seat E'', in which the head F' of the valve-stem F'' rests when closed, the valve being carried by a screw-plug F'', screwed into the offset F' of the passage F. By this the complete supply of steam and water may be cut off, so that the chamber G can be cleaned without stopping the delivery of steam.

By constructing a water-gage as described it will be seen that the valve will work automatically if the glass tube should break, as the sudden rush of steam and water against the head I' of the valve-stem I will close the passage J, thereby preventing any damage being done by the overflow of water if the engineer should happen not to be near.

It will be seen that I provide means so that the valve can be operated by the hand, if desired.

It will be seen by connecting the passages of one of the casings by an auxiliary passage controlled by a valve I provide a gage that will prevent the breaking of the glass tube, as now is the case when a new glass tube has been inserted and the flow of steam and water is allowed to rush into the tube before it has time to become heated to the temperature of the boiler.

It will be noted that owing to sectional area of the stem I on one side of the valve J' the area upon which the steam can act is less on this side than upon the opposite side, where the entire cross-sectional area of the valve is acted upon by the steam.

Having thus fully described my invention, what I claim as new, and desire to secure by Letters Patent, is—

1. In a water-gage for boilers, the combination with an upper and lower casing, of a glass tube connecting the said casings, a plug carried by each casing, for connecting it to the boiler, a passage formed in the plug, a chamber provided with an automatic valve closing a passage leading to the glass tube and a passage connecting the passage in the

2
plug to the passage leading into the glass tube and an auxiliary valve adapted to close the passage connecting the plug to the chamber, for the purpose described.

5 2. In a water-gage for boilers, the combination with an upper and lower casing, of a glass tube connecting the said casings, means carried by each casing for securing it to the boiler, a passage leading into the casing provided with a valve-seat at its end, a chamber provided with an automatic valve closing the passage leading to the glass tube, and an auxiliary valve closing the passage leading into the casing and a passage connecting the said 15 passages, as set forth.

3. In a water-gage for boilers, the combination with an upper and lower casing, of a glass tube connecting the said casings, a plug provided with a passage leading into a chamber in each casing, a passage leading into the glass tube, means for closing said passage, and means for closing the passage in the plug and an auxiliary passage connecting the passage in the plug to the passage leading to the 20 glass tube, for the purpose described.

4. In a water-gage for boilers, the combination with an upper and lower casing, of a glass tube connecting said casings, a plug provided with a passage leading into a chamber in said casing, a valve-seat formed at the 25 end of said passage a valve working in said

chamber, adapted to be seated in said valve-seat, a passage leading from said chamber to the glass tube, a valve closing said passage and a passage connecting the two said passages controlled by a valve for the purpose 35 described.

5. In a water-gage for boilers, the combination with an upper and lower casing, connected by a glass tube, a passage leading into 40 the casing provided with a valve-seat, at its end, a chamber connected to the said passage by a passage, said passage being provided with a valve, said chamber being provided with an automatic valve closing the passage 45 leading to the glass tube, and an auxiliary passage connecting the passages leading to the boiler and the glass tube said passage being controlled by a valve, as set forth.

6. In a water-gage for boilers, the combination with an upper and lower casing, of a chamber formed in said casings, of a plug provided with a passage valve-controlled leading into each chamber, a passage leading from each casing, a glass tube connecting 50 said passages and a passage connecting the passage in the plug, with the passage leading to the glass tube, for the purpose described.
